UNITED STATES PATENT OFFICE

152,219

DESIGN FOR A CUTLERY DISPLAY CASE

Howard M. Schick, Lee's Summit, Mo.

Application December 23, 1947, Serial No. 143,291

Term of patent 14 years

(Cl. D80—9)

To all whom it may concern:

Be it known that I, Howard M. Schick, a citizen of the United States, residing at Lee's Summit, in the county of Jackson and State of Missouri, have invented a new, original, and ornamental Design for Cutlery Display Case, of which the following is a specification, reference being had to the accompanying drawing, forming part thereof.

Fig. 1 is a perspective view of a cutlery display case, showing my new design.

Fig. 2 is a partial plan view of the cutlery display case.

Fig. 3 is an end elevation of the cutlery display case.

I claim:

The ornamental design for a cutlery display case, as shown.

HOWARD M. SCHICK.
